(57) **CLAIM**

The ornamental design for a miniature motor with reduction worm gear unit, as shown.

DESCRIPTION

FIG. 1 is a top plan view of a miniature motor with reduction worm gear unit showing my new design;

FIG. 2 is a front elevational view thereof;

FIG. 3 is a bottom plan view thereof;

FIG. 4 is a right side elevational view thereof;

FIG. 5 is a left side elevational view thereof;

FIG. 6 is a rear elevational view thereof;

FIG. 7 is a perspective view from upper right of front thereof; and,

FIG. 8 is a perspective view from lower left of rear thereof. The broken line showing of the environment is for illustrative purposes only and forms no part of the claimed design.
